[57] **CLAIM**

The ornamental design for a wristwatch, as shown and described.

DESCRIPTION

FIG. 1 is a top plan view of a wristwatch showing my new design;

FIG. 2 is a bottom plan view thereof;

FIG. 3 is a front elevational view thereof with the band removed for ease of illustration, the rear view being substantially a mirror image;

FIG. 4 is a right side elevational view thereof with the band omitted for ease of illustration; and,

FIG. 5 is a left side elevational view thereof with the band omitted for ease of illustration.

FIG. 1

FIG. 2

FIG. 3

FIG. 4

FIG. 5
